HOWARD ASSIGNOR TO SAID LOSEE.

MIXTURE-HEATER.

1,315,730.

Specification of Letters Patent.

Patented Sept. 9, 1919.

Application filed August 28, 1918. Serial No. 251,794.

To all whom it may concern:

Be it known that we, JOSEPH S. LOSEE and FRANK A. HOWARD, citizens of the United States, residing at Hebron, in the county of 5 McHenry and State of Illinois, and Chicago, in the county of Cook and State of Illinois, respectively, have invented new and useful Improvements in Mixture-Heaters, of which the following is a specification.

10 Our invention relates to improvements in mixture heaters for internal combustion engines and will be fully understood from the following specification, taken in connection with the accompanying drawing, in which—
15 Figure 1 is a side elevation of a mixture heater constructed in accordance with the invention, the casing of the heater being shown in longitudinal section; Fig. 2 is a longitudinal section through the heater and 20 casing, the elbows being removed; and Fig. 3 is a section on the line 3 of Fig. 2.

In the design of the present mixture heater we have proceeded upon the theory that for the handling of mixtures of relatively heavy hydrocarbon fuels, such as present day motor gasoline, the most satisfactory results will be obtained by supplying the heat directly to the unvaporized fuel particles in the mixture. We have found 25 by test that even where the air for carburation is at such a temperature as to insure complete vaporization of the liquid fuel in time, this result is not in fact accomplished within the carbureter or intake conduits of 30 the ordinary internal combustion engine, for two reasons, *i. e.*, the liquid fuel is not reduced to a fine enough state of subdivision by the action of the spray nozzle of the carbureter, and the transfer of heat from 35

40 the air to the fuel particles is not sufficiently rapid to complete their vaporization in the length of time in which the fuel traverses the intake conduit and enters the engine cylinder. It is of course true that there is a 45 continued vaporizing action during the inlet and compression strokes of the piston in the engine cylinder and in some cases this additional time element may be sufficient to permit the complete vaporization of the bulk 50 of the fuel but it is necessarily true that a certain proportion of the unvaporized fuel which enters the cylinder is deposited upon the lubricated walls thereof, diluting the film of lubricant on the walls and by admix-

ture with this lubricant having its vapor 55 tension so reduced that vaporization proceeds very slowly. The demonstrated result of this phenomenon is the accumulation within the crank-case of the engines of the heavier fractions of the liquid fuel, this accumulation being in many cases more rapid than the loss of lubricant, so that the oil reservoir or circulating system will in fact appear to be manufacturing lubricating oil 60 instead of consuming it.

We have found that it is readily possible without altering the general design of the engine or carbureter, or changing the character of fuel, to overcome all of these disadvantages. The remedy for the situation 70 which is represented by the present invention does not reside primarily in raising the temperature of the air or of the mixture but rather in applying a small quantity of heat 75 efficiently in such manner that it shall exert its main effect in making up the loss of latent heat of vaporization of the fuel. This result is in general attained by the use of an element inserted in the mixture passage and so designed as to act as a separator for 80 throwing out of the mixture stream the suspended, unvaporized fuel particles therein, and causing these particles to impinge upon metallic surfaces which are maintained at a moderately high temperature.

It has been our special purpose to provide 85 a device capable of efficiently performing these functions without causing any appreciable loss in volumetric efficiency of the motor either by unduly heating and thus expanding the mixture, or by imposing such resistance to its flow as to give a perceptible drop in density.

The mixture heater in accordance with the 90 present invention, which is illustrated by the accompanying drawing, is in the form of a casting having flanges 10 and 11 at its end for attachment to the mating flanges of the carbureter and intake manifold of the engine. Between these flanges the body portion of the casting is expanded laterally to 95 an internal diameter approximately twice the bore of the intake passage. In the construction shown, this expanded portion of the heater is not symmetrically arranged 100 with respect to the flanges, being offset toward one flange, as shown by the broken section-line 3, 3 on Fig. 2. By virtue of this

lack of symmetry there is obtained a clearance space behind the flange 10 sufficient for the application of a nut to the end of the bolt or stud 12, by which the mixture heater 5 is secured in place. As appears from Fig. 2, there is not sufficient space behind the flange 11 for a nut, and this flange must therefore be secured by a cap-screw entering a threaded aperture 13, or by a stud set 10 in this aperture. By this construction, which permits of the use of a nut back of the flange for securing the device on one end and of a stud or cap-screw on the other, in combination with an internal construction 15 which is symmetrical with respect to the two ends, as will later be described, it is possible to apply the mixture heater between the carbureter and manifold, or between the carbureter and the engine casting where no 20 separate manifold is employed, regardless of the type of flange-securing means used in any particular instance.

The entire exterior surface of the expanded portion of the body casting is checkered 25 or otherwise roughened, as shown at 14, to provide a maximum surface for contact with the heating gases. Halfway between the flanges 10 and 11, and therefore somewhat offset from the center of the expanded section, there is a flange 15, the purpose of which 30 is to provide sufficient depth of metal to permit of drilling and tapping at any point around the circumference of the heater, for the fastening of the screws 16 (Fig. 1) by 35 which the jacket-casing and elbow connections therefor are secured. This jacket-casing 17, which may be formed either of one piece or of two pieces of smooth sheet-metal, is preferably expanded in the center, as illustrated, and has truly cylindrical end portions 40 which rest in grooves 18 in the inner edges of the flanges 10 and 11. The jacket-casing is perforated at diametrically opposite points and formed to receive the ends 45 of a pair of flattened elbows 19 by which the heating gas is circulated through the jacket.

Mounted centrally within the expanded body portion of the casting there is a deflector member 20, which is circular in all 50 cross-sections and symmetrical with respect to its transverse central sectional plane. Between the outer surface of the deflector member 20 and the inner surface of the expanded 55 body casting there are arranged four generally helicoidal ribs designated 21, these ribs representing helices of very long pitch, for example, a pitch four times the length 60 of the deflector 20. The helicoidal ribs 21 are also preferably of decreasing thickness from the center toward their ends, as shown in Fig. 2. Both the inner surface of the expanded body portion and the outer surface 65 of the deflector 20 are preferably grooved or corrugated, the corrugations be-

ing on helical lines parallel with the ribs 21. This construction very much increases the effective area of the surfaces and is believed to have an additional beneficial effect, which will be later pointed out. We 70 have found that the entire mixture heater, that is, the body portion, the deflector and the ribs, may be conveniently made as an integral casting, it being possible, likewise, to cast the jacket-cover 17 as an integral 75 part of the heater. We do not recommend this latter construction, however, except in special instances.

As will be seen from Fig. 2, the depth or thickness of the four helicoidal passages outlined by the ribs 21, deflector 20 and inner surface of the body, decreases as the passages approach the maximum diameter of the deflector, the effect being to preserve a mixture passage of substantially uniform cross-sectional area throughout. We have even found it possible to slightly decrease the cross-sectional area of the mixture passages as represented by the section shown in Fig. 3 without a sensible loss of head of the mixture, the contraction and expansion being so gradual that the Venturi-tube principle applies in a measure. This is highly advantageous, since the separating action, as the result of which the unvaporized fuel particles are thrown against the heated surfaces, increases with the velocity.

In the operation of our mixture heater the same is inserted as a part of the inlet passage of the engine, preferably by attachment between the mating flanges of the carbureter and manifold, as described. One of the elbows 19 is connected with the water-circulation system or the exhaust pipe of the engine, preferably the latter, since with the 105 heavier grades of fuels now available the temperature of the circulating water is hardly sufficient to effect complete vaporization of the fuel and furthermore, a considerable time is required for heating the entire body of the water in the circulating system, whereas the heated exhaust gases are available as soon as the motor comes into operation. The mixture formed in the carbureter impinges upon the deflector 20 and 110 is divided into four helicoidal streams by the ribs 21. It will be noted that the path of the gases in these helicoidal passages is such that centrifugal force is brought into play to the maximum extent with a minimum change in direction of the gases, or more accurately, with a minimum resistance to flow. The helicoidal twist of the ribs 21 of course tends to throw out of the mixture stream the unvaporized fuel particles 120 thereof against the surfaces of these ribs, while the outward and inward curvature of each passage following the walls of the deflector 20 brings the action of centrifugal force into play in a plane at right angles to 125 130

the force brought into play by the helicoidal twist. As the result of this double curvature of each of the four mixture passages the entrained fuel particles are effectively separated from the mixture stream, and furthermore, such separation is not effected at a single point or on a small surface but takes place throughout the length and over all of the surfaces of the heater, wetting all of these surfaces and forming a film thereon which is subjected to the direct heating effect of the exhaust gases transferred through the metal walls. Under such conditions the film is vaporized as it is deposited, with the result that the mixture issuing from the heater contains the same proportions of fuel and air as that entering the heater, the sole difference being that the entering stream carries the fuel largely in the form of unvaporized liquid droplets, while the issuing stream carries the fuel almost entirely in the form of vapor or at least in atoms or droplets which are so small as to approach the vesicular condition and remain permanently in suspension. We find that the mixture heater design illustrated does not depend for its efficiency solely upon the supply of heat to the fuel but acts likewise as an efficient mechanical device for breaking up the larger fuel particles and preventing the irregularities of motor action which result from the formation of slugs of liquid fuel.

The particular design of mixture heater herein described is especially desirable for attachment to existing motors, in that it is of such small length as to be capable of insertion between the carburetor and manifold or cylinder-block in almost all cases. The mixture passage or multiple of passages within the short length of the heater is nevertheless of such design that it is capable of efficiently performing its functions and that without imposing any appreciable resistance to the flow of the mixture or materially heating and thus expanding the mixture and causing loss of volumetric efficiency of the motor, an objection which has heretofore been common to practically all mixture heater designs in which the heat supply was sufficient to thoroughly dry the mixture. We believe that the successful operation of the present design is primarily due to the fact that all of the surfaces therein are arranged to give up heat rather to the unvaporized fuel particles than to the air.

While we have in the foregoing described in considerable detail a preferred embodiment of our invention, together with our theories as to the manner in which the same operates, it will be understood that this is illustrative only, for the purpose of making the invention more clear and that the invention is not to be regarded as limited to the details described nor as dependent upon

the soundness or accuracy of the theories which we have advanced, except in so far as such limitations form a part of the accompanying claims, in which it is our intention to claim all novelty inherent in the invention as broadly as is permissible in view of the prior art.

What we claim is:

1. A mixture heater forming a part of the intake passage of an internal combustion engine and comprising a jacketed hollow member continuously increasing in diameter from its ends to its central section, a deflector of cross-section similar to that of the hollow member and of double conical longitudinal section supported centrally within said hollow member and forming therewith an annular mixture passage which decreases in thickness from the ends toward the center, means for supplying heating fluid to the jacket of said member, and means for supplying heat by conduction from the said member to the deflector.

2. A mixture heater forming a part of the intake passage of an internal combustion engine and comprising a jacketed hollow member of circular cross-section continuously increasing in diameter from its ends to its central section, a double conical deflector supported centrally within said hollow member and forming therewith an annular mixture passage, a plurality of ribs disposed longitudinally of the passage and joining the said deflector and body to subdivide the annular passage, and means for supplying heating fluid to the jacket of the said member.

3. A mixture heater forming a part of the intake passage of an internal combustion engine and comprising a jacketed body portion having a mixture passage therein continuously increasing in diameter from its ends toward its central section, a deflector centrally mounted within the passage and of gradually increasing diameter from its ends toward its central section, a plurality of generally helicoidal ribs joining the deflector and the body, and means for supplying heating fluid to the jacket of the said body.

4. A mixture heater comprising an integral casting including end flanges, a hollow body portion of circular cross-section and of a diameter continuously increasing from the flanges toward the center, a deflector centrally mounted within the body portion and of similar section to form an annular mixture passage, and a plurality of longitudinal ribs joining the deflector and body portion and subdividing the said passage longitudinally, in combination with a separable sleeve resting on the said flanges and forming with the latter a jacket space for heating fluid.

5. A mixture heater comprising an in-

tegral casting, including end flanges, a hollow body portion of circular cross-section and of a diameter continuously increasing from the flanges toward the center, a deflector centrally mounted within the body portion and of similar section, and a plurality of longitudinal, helicoidal ribs joining the deflector and body portion, and a separable sleeve forming with the outer wall 10 of the body an annular jacket space for the circulation of a heating fluid.

6. A mixture heater comprising a centrally expanded body portion of circular cross-section and circular securing flanges 15 formed integrally with the ends of said body portion, one of said flanges only being spaced from the central expanded portion by a distance sufficient to permit of the application of a securing nut on the inner face 20 of the flange, and a separable sleeve resting on the peripheries of the said flanges to form an annular jacket chamber within which the securing nuts are located.

7. A mixture heater designed for attachment to an internal combustion engine to form a part of an intake passage thereof and comprising an integral body having end-securing flanges of circular cross-section in combination with a detachable jacket casing 30 fitted to the peripheries of the said flanges, and fittings carried by the said casing for

the attachment of fluid-inlet and outlet pipes, whereby the casing may be angularly adjusted with reference to the integral body and removed therefrom without altering the 35 body.

8. A mixture heater for internal combustion engines and adapted to form a part of the mixture passage of such engines and comprising means forming a plurality of 40 separated mixture passages each curving outwardly and then inwardly and helically around the projected axis of the mixture passage, the aggregate area of all of said passages throughout their lengths being substantially equal to the area of the mixture passage, and means for heating the surfaces bounding the said mixture passages. 45

9. A mixture heater forming a part of the intake passage of an internal combustion engine and comprising a jacketed body portion having a mixture passage therein, a plurality of generally helicoidal ribs projecting radially into the mixture passage, helicoidal corrugations generally parallel with the said ribs and formed in the surface of the mixture passage, and means for supplying heating fluid to the jacket of the 50 55 said body.

JOSEPH S. LOSEE.
FRANK A. HOWARD.
